UNITED STATES PATENT OFFICE.

CHRISTIAN GULBRANSEN, OF CHICAGO, ILLINOIS, ASSIGNOR TO GULBRANSEN COMPANY, OF CHICAGO, ILLINOIS, A CORPORATION OF ILLINOIS.

PLAYER GRAND PIANO.

Application filed October 26, 1923. Serial No. 870,875.

My invention relates to a grand piano with player mechanism incorporated therein.

In putting player mechanism in an upright piano to develop a unitary structure of pleasing appearance and efficient mechanical arrangement relatively little difficulty is encountered because the spaces in front of the strings above and below the keyboard are conveniently arranged for housing the tracker bar and roll winding mechanism, and the power mechanism, respectively.

In a grand piano the frame and strings are set on three legs and except for the lyre supporting the foot pedals, the entire space below the same is open and unobstructed. The cover above the strings has to be hinged to tilt up for acoustical reasons, and this leaves the playing mechanism very much in need of suitable housing facilities. The grand piano is, furthermore, of a pleasing and regular contour very much standardized by long usage.

My invention is primarily concerned with two matters:—first, the mechanical problems incident to incorporating player mechanism in this structure without disfigurement thereof, and with as little departure from the attractive shape and appearance of the original piano as possible, to produce an instrument capable of harmonizing with the most carefully designed interiors as distinguished from a mere mechanical music box using a horizontal piano frame and strings; and, second, ease of assembly and alteration, and access for adjustment and repair. This last includes facilities for removing and replacing the more conspicuous parts of the player mechanism without requiring the services of a mechanic skilled in the special art of adjustment and repair of player actions and pneumatic piano player actions.

Advantageous control features and correlations between the controls for playing by hand and with the player mechanism are also involved.

In the accompanying drawings:

Figure 1 is an isometric view of a player piano according to the invention;

Fig. 2 is a front elevation of the same;

Fig. 3 is a side elevation of the same;

Fig. 4 is a bottom plan view of the piano case with the legs and downwardly projecting parts in section;

Fig. 5 is a transverse section of the pneumatic stack and action;

Fig. 6 is a partial plan view with the cover removed;

Fig. 7 is an enlarged detail of a connecting head in section on line 7—7 of Fig. 8;

Fig. 8 is a section on line 8—8 of Fig. 7; 60

Fig. 9 is a partial front elevation showing the main control connections; and

Figs. 10, 11 and 12 are fragmentary details of mechanical connections for the control system. 65

In the embodiment of the invention selected for illustration, the player mechanism itself may conveniently be considered as made up of four parts: power mechanism, storage means, the pneumatic action or stack, 70 and the roll box. In considering the problem it is well to bear in mind the limitations on the locations that can be assigned to the various parts.

Obviously, the foot pedals, i. e., the power 75 mechanism, has to be beside the lyre to be accessible to the feet of the operator, and the roll box must be in such a position in use that the operator can see the music sheets. Subject to these two relatively important limitations, a fairly wide range of position for the parts is available.

Referring now to Figures 1 to 4 inclusive, it will be observed that the power mechanism comprises a cross piece 10 fastened to the rear faces of the lyre standards 12. At opposite ends this board carries the depending bellows 14 to which the foot pedals 16 are connected by any suitable collapsible linkage 18—18. Board 10 contains suitable valve passageways communicating with tubes 20 extending rearwardly across the bottom of the pneumatic stack 22. It will be apparent that board 10 and the pneumatics and the foot pedals carried thereby can be removed as a unit by simply unfastening board 10 from standards 12, and slipping the ends of tubes 20 off the connectors carried by board 10.

Through connectors 24, tubes 20 communicate with tubes 26 leading to the wind chest 28 fastened to the bottom of the frame 30 of the piano casing. The usual bellows reservoirs 32 co-operate with the wind chest to provide the requisite storage of power. 105 From the wind chest main conduit 34 leads to the channel board space 36 (see Fig. 5) of the pneumatic stack 22.

The rewind pneumatic 38 with its primary control pneumatic 40 is positioned with the 110

wind chest and reservoirs under the frame. Except when rewinding, the supply to the roll box motor is passed through the usual suction change control means 42 for regulating the speed of movement of the sheet over the tracker bar. Control 42 is actuated in any suitable or preferred manner as by slide 44 operated by crank arm 46 on shaft 48, and in turn actuates a slide 50 carrying an indicator 52. The primary governor for the motor speed is the usual pneumatic 54 biased by leaf spring 56. This governor is mounted with the wind chest under the frame 30.

Any suitable pneumatic stack may be employed. The one illustrated comprises, briefly, the channel boards 58 and the banks of pneumatics 60 mounted thereon. Brackets 62 provide pintles 64 at opposite sides 20 of the bed 66 and hinged members 68 fastened directly to the stack support the same for pivotal movement on pintles 64. In the position of use, an arm 70 rigid with hinge member 68 is fastened in the position shown 25 in Figure 5 by retaining pin 72.

The stack is provided with a rear board 74, a bottom board 76, and a front board 78 to provide complete enclosure on three sides, and when in assembled position a cleat 80 30 fills the gap between rear board 74 and bed 66. Without sealing off the enclosure so as to interfere with the action of the pneumatics, this cuts it off from such circulatory air currents as might tend to fill the casing 35 with dust and dirt.

The keyboard and piano action are mounted on a separate action board 82 which carries the pivot strip 84 and the rear cushion 86. The keys are articulated by an elbow 40 joint comprising a pintle 88, the parts of the key coming into abutment at 90. The piano action may be of any suitable type, and as such actions are well known, a detailed description thereof is deemed superfluous. It comprises, briefly, the lifter 92 45 actuating the wippen 94 pivoted at 96, said wippen carrying the usual sticker escape- ment 98 and fly jack 100 to actuate the ham- mer 102.

The hammer rail is divided into two equal sections 104 and 106. The rear end of each key terminates in a projection 108, which overlie risers 112.

Risers 112 constitute means for intercon- 55 necting the pneumatic stack and the piano action by simple juxtaposition of the parts. It will be noted that action board 82 can be freely withdrawn to the left from the position shown in Fig. 5, and that the stack 60 may be swung on its pivot 64 for convenient access thereto or removal thereof. Risers 112 are supported on bed 66 and guided through a cleat 114. Their upper heads 116 underlie projections 108 when the piano ac- 65 tion is placed in proper position, and their

lower heads 118 overlie the striker rods 120 of the pneumatic stacks when the latter is also placed in proper assembled position. Removal of the piano action does not affect the condition of adjustment of the risers, 70 and removal of the pneumatic stack merely lets heads 116 down a trifle to rest on bed 66.

For convenience in the installation and removal of the pneumatic stacks, I provide connectors 121 in cleat 114 normally receiving the ends of short tubes 122 leading from the individual connectors 124 for the pneumatics 60. The stack can be swung back from the position shown in Figure 5 for access without disconnecting tubes 122, and if it is desired to remove the stack entirely, these tubes can readily be slipped off either connectors 124 or connectors 121. As these two sets of connectors are both arranged in alignment across the width of the piano, no difficulty is encountered in connecting the tubes up again to the right connectors.

The damper rail, (see Fig. 9) is also separated at 126 into the two parts 128 and 130. Part 130 carries a projection 132 underlying the end of part 128.

When playing the piano by hand it is customary to provide a pedal with connections for lifting the entire hammer rail for playing softly. This is the left-hand pedal 134 actuating rod 136 suitably connected as by levers 138 and 140 (see Fig. 12) pivoted in the piano bed with riser 142 terminating in head 144 underlying the adjacent ends of both hammer rail sections 106 and 104.

The bass sustaining pedal 146 is in the middle, and actuates rod 148 connected through actuating levers 149 and 150 pivoted at 152, which lever carries head 154 underlying section 128 to raise the bass dampers. Suitable spring means such as leaf spring 156 overlying the end of lever 150 are provided for normally holding the parts in the position shown in Fig. 9.

The right-hand pedal rod 158 is suitably connected by levers 160 and 162 (see Fig. 11) pivoted in the piano bed to riser 164 underlying section 130. By reason of projection 132, this pedal lifts all of the dampers.

Only one sustaining control is provided for playing with the pneumatic mechanism. This comprises manual control crank or finger piece 166 actuating a bell crank 168 through crank 169 and link 172. Bell crank 168 operates riser 171 underlying the end of damper rail 130, whereby it operates to raise section 128 also.

Selective control of the loudness for the sections of the keyboard corresponding to the hammer rail sections 104 and 106 is provided. I have illustrated finger piece 172 and a transmission including link 174, rocker 176, link 178, bell crank 180 and riser 182 for lifting the treble portion of the

hammer rail 104, with a suitable biasing spring 184 adapted to carry nearly all the weight of hammer rail section 104 to make operation of the parts relatively easy. Similarly, I have provided finger piece 186 and a transmission including link 188, rocker 190, link 192 and bell crank 194 for actuating riser 196 to lift the bass hammer rail section 106. This linkage is also provided with a suitable balancing spring 198.

The roll box is a rigid unitary structure defining two casings 200 and 202 for housing the roll motor and associated transmission and control parts. The roll 204 is held in the space between the two casings by the usual roll holders.

This constitutes the entire roll box a unitary structure which may be suitably attached to the top of the piano casing, or readily removed therefrom. The front of the roll box structure is rearwardly inclined as clearly shown in Figure 3, and a suitable grooved strip 206 is positioned just in front of the same. Slidable panels 208 and 210 may be moved to the position shown in Figure 1 to completely cover the front of the roll box and form an effective support for the music to be used when playing without the pneumatic mechanism or slid laterally to either side to expose the roll and roll holding devices, when the pneumatic playing mechanism is to be employed.

To facilitate complete removal of the entire roll box and substitution of an ordinary music rack therefor, I have provided quick detachable connections between the roll box and the stack 22. From cleat 114, tubes 212 extend laterally to either side of the frame 214 and then above the same as at 216 for connection to multiple heads 218. From the tracker bar the corresponding tubes pass out of either end of the roll box to registering heads 220.

Referring now to Figures 7 and 8, it will be seen that each head 218 is pierced by a regular pattern of tubular apertures 222, each aperture receiving a connector 224, which connector in turn receives the end of one of the tubes 212. Heads 220 contain duplicate passageways similarly arranged, and duplicate connectors to which are connected the tubes 226 running to the roll box. Fastening screws 228 clamp the heads securely together, and a centering pin 230 carried by head 220 and entering a registering aperture in head 218 prevents assembly except in one predetermined position. To provide a tight seal for passages 222, a suitable gasket 232 with a registering pattern of apertures is interposed between the heads before they are fastened together.

It will be seen that by uncoupling heads 218 from 220, the roll box and heads 220 can be completely removed and laid aside, heads 218 and their connections to cleat 114

and the pneumatic stack remaining undisturbed. By removing the foot pedals and pumping mechanism as above pointed out, the entire instrument is transformed substantially into an ordinary grand piano, as all the other parts of the pneumatic mechanism are mounted close up under the bottom of the piano casing out of sight. It will also be obvious that any relatively unskilled person can readily connect and disconnect heads 218 and 220 in a short space of time.

Without further elaboration, the foregoing will so fully explain the gist of my invention, that others may, by applying current knowledge, readily adapt the same for use under various conditions of service, without eliminating certain features which may properly be said to constitute the essential items of novelty involved, which items are intended to be defined and secured to me by the following claims.

I claim:

1. In a player grand piano, a casing, frame, strings, bed and piano action, a roll box on the top of the frame serving also as a music stand, a tracker bar in said roll box, a player action fastened to the bottom of the bed, and having striker rods, a cleat fastened to the bottom of the bed above the player action striker rods, vertically slideable extensions in said cleat riding on the player action striker rods and connecting them to the piano keys, pneumatic tubes connected to said player action, connectors in said cleat receiving said tubes, tubes extending from said cleat connectors above the frame, tubes leading from the tracker bar out of said roll box, and detachable connecting means above the frame for connecting the tubes from the tracker bar with the tubes from the cleat.

2. In a player grand piano, a bed, a player action below said bed, supporting brackets on said bed, a pivotal connection between said action and said brackets, and a set of connectors for the control tubes for said action mounted on the under side of said bed in position to be exposed by said pivotal movement of said bed.

3. In a player grand piano, a bed, a player action below said bed, supporting brackets on said bed, a pivotal connection between said action and said brackets, a set of connectors for the control tubes for said action mounted on the underside of said bed in position to be exposed by said pivotal movement of said action, a tracker bar, and tubes leading from said connectors to said tracker bar.

4. In a player grand piano, a bed, a keyboard and piano action entirely above the bed, a player action entirely below the bed, connections mounted in the bed independent of both actions for interconnecting them, a pivotal support for said player action for

swinging it to one side to gain access to said connections, and control tubes leaving said player action a short distance below the pivotal axis.

5. In a player grand piano, a bed, a keyboard and piano action entirely above the bed, a player action entirely below the bed, connections mounted in the bed independent of both actions for interconnecting them, a pivotal support for said player action for swinging it to one side to gain access to said connections, control tubes leaving said player action a short distance below the pivotal axis, and connectors for said tubes mounted on the underside of the bed at one side of said pivotal axis.

6. In a player grand piano, the pedal lyre frame extending downwardly from the piano body, a pneumatic action extending across under the piano bed behind said lyre frame, a supporting board extending transversely of and secured to the lyre frame be-

low the piano bed, a pair of pumping bellows secured to said board at either side of said lyre frame, and foldable pedal structures supported on said bellows.

7. In a player piano, a bed, a player action supported below said bed, a keyboard and hammer mechanism above the bed; a tracker bar above the bed, tubes leading from said tracker bar to a position below the bed, tubes leading from the player action, a junction cleat supported on the underside of said bed and having junction passageways for connecting said tracker bar tubes with said player action tubes, and striker rods extending through said bed for connecting said player action with said hammer mechanism, said junction cleat having guide passageways for said striker rods.

In witness whereof, I hereunto subscribe my name this 3 day of October, 1923.

CHRISTIAN GULBRANSEN.
